Frederick Peters
By *Frederick Peters*

UNITED STATES PATENT OFFICE.

FREDERICK PETERS, OF DETROIT, MICHIGAN, ASSIGNOR, BY MESNE ASSIGNMENTS, TO CHARLES F. BACKUS, OF DETROIT, MICHIGAN.

LEDGER.

SPECIFICATION forming part of Letters Patent No. 724,496, dated April 7, 1903.

Application filed March 10, 1902. Serial No. 97,620. (No model.)

To all whom it may concern:

Be it known that I, FREDERICK PETERS, a citizen of the United States, residing at Detroit, in the county of Wayne and State of Michigan, have invented certain new and useful Improvements in Ledgers, of which the following is a specification, reference being had therein to the accompanying drawings.

The invention has particular reference to loose-leaf ledgers of that type wherein the ledger-covers are capable of being moved to or away from each other to permit of the insertion of ledger-leaves and the subsequent clamping of the ledger contents.

15 The invention consists in a novel form of mechanism for moving the covers and in the peculiar construction and combination of the various parts thereof, as will be fully herein-after described, and shown in the drawings, 20 in which—

Figure 1 is a sectional perspective view of a ledger embodying my invention. Fig. 2 is a detached plan view of the housing and the winding mechanism therein; and Fig. 3 is a 25 section on line xx , Fig. 2.

The reference-letter A designates the upper or top cover of the ledger, and B the lower complementary cover, and C and D represent hinged strips secured to and forming part of 30 the covers, as shown in Fig. 1.

E and F designate back plates carried by the covers, which are adapted to protect the rear edges of the ledger-leaves, and G designates posts, which may be of any suitable 35 type for adjustably securing the covers to each other. In practice I preferably employ extensible posts, consisting of tubular members a , secured to a plate a' upon the strip portion D of the cover B, and complementary 40 tubular post members b , attached to the housing H, which is in turn secured to the strip C in any suitable manner. The post members are adapted to engage one within the other, as shown, and within the central post 45 I insert a coiled spring I of a length substantially equal to the length of the extended post in which it is arranged. The spring is adapted to bear against the lower hinged strip and the housing and acts normally to 50 separate the covers, holding them at a con-

siderable distance apart to permit of the ready insertion of the ledger-leaves.

The letter J designates a winding mechanism for drawing the covers together against the tension of the spring I to clamp the 55 ledger-contents. This mechanism is located within the housing H and is of the following construction:

K is a main operating-shaft journaled in bearings L in the housing, one end of which 60 is squared, as at c, and extends through an aperture e in the housing into close proximity to the ledger side nearest the operator. Fixed upon this shaft are the drums g, one above each end post, and h designates cables or 65 straps, connected one to each drum, extending through apertures i in the housing into and through the hollow posts. The supporting-plate a' is apertured, as at a², at its ends to receive the end posts, and b' is a cable-guide extending across each aperture and secured to the supporting-plate, as shown. The free end of each cable extends over its 70 guide and is connected to the cover opposite to that carrying the housing, as shown in 75 Fig. 1. The particular fastening means for each cable end consists of a clamping-plate a³, located within a recess a⁴ in the strip D. This clamp is secured by means of a screw a⁵ to the supporting-plate a' and clamps the 80 cable end to said plate, as shown.

O designates a ratchet-wheel fixed upon the shaft, preferably at its center, and P is a dog engaging the wheel, which is provided with an operating-handle Q. The handle described is journaled in the shaft-bearings and is provided with a squared end p², which projects into an aperture e², formed in the housing immediately beneath the aperture e.

R is a coil-spring attached to the arm Q and 90 to one of the bearings and acts upon the dog to keep the latter in engagement with the wheel.

From the above description of my device it will be seen that by means of a suitable key 95 A' by turning the shaft K the covers will be drawn together to produce the clamping effect desired and will also be locked in their clamped position by the dog. By engaging with the key the end of the arm Q and turn-

ing the latter the covers will be released and immediately thrown apart automatically by the spring I, leaving the ledger in condition to have additional leaves added or leaves withdrawn. It will also be noticed that by having the mechanism for actuating the covers arranged as set forth I am enabled to operate the covers without the necessity of turning the ledger from its position in use.

10. What I claim as my invention is—

1. In a ledger, the combination with the complementary covers, of extensible connecting-posts therefor, a rotatable member carried by one of the covers, a flexible binding device connecting the complementary cover with said rotatable member and adapted to be wound upon the latter, and means for operating the rotatable member.

2. In a ledger, the combination with the complementary covers, of extensible connecting-posts therefor, a rotatable member carried by one of the covers, a flexible binding device detachably secured at one end to the complementary cover and attached at its opposite end to the rotatable member and adapted to be wound upon the latter, and means for operating said rotatable member to clamp the ledger contents.

3. In a ledger, the combination with the complementary covers, of a hollow connecting-post therebetween, a winding-shaft carried by one of the covers, and a flexible binding device extending through the post and secured at its ends to the complementary cover and winding-shaft.

4. In a ledger, the combination with the complementary covers, of an extensible connecting-post therebetween, a winding-shaft carried by one of the covers, a drum thereon, a strap adapted to be wound upon the drum and connecting the latter with the complementary cover, and means for operating the shaft.

5. In a ledger, the combination with the complementary covers, connections therebetween permitting relative movement of the covers, a winding-shaft carried by one of said covers extending in adjacency to the inner side of the ledger, a flexible winding device connecting said shaft and the complementary cover and adapted to be wound upon the shaft, a ratchet-wheel upon the shaft, a spring-actuated dog engaging the ratchet-wheel, and an operating-arm extending substantially parallel with the shaft to and operable at the inner side of the ledger.

6. In a ledger, the combination with the complementary covers, of a hollow extensible

post therebetween, a winding-shaft journaled in bearings carried by one of the covers, and a flexible connecting member, extending through the post, secured at one end to and adapted to be wound upon the shaft, and connected at its opposite end to the complementary cover.

7. In a ledger, the combination with the complementary covers, of a hollow extensible post therebetween, a winding-shaft journaled in bearings carried by one of the covers, and a flexible connecting member, extending through the post, secured at one end to and adapted to be wound upon the shaft and detachably connected at its opposite end to the complementary cover.

8. In a ledger, the combination with the complementary covers, of a hollow extensible connecting-post therefor, a winding-shaft journaled in bearings carried by one of the covers, a band or strap extending through the post, and connected at its ends to the shaft and the complementary cover, and a guide member for centering the band or strap within the post.

9. In a ledger, the combination with the complementary covers, of a tubular extensible connecting-post therebetween, a shaft journaled in bearings carried by one of the covers, a winding-drum upon said shaft arranged over the post, a band or strap, extending through the post, connected at one end to the drum and detachably connected at its opposite end to the complementary cover, and a guide-bar for said band or strap extending diametrically across the post end opposite the drum.

10. In a ledger, the combination with the complementary covers, of extensible connecting-posts therebetween, a winding-shaft journaled in bearings carried by one of the covers, and a band or strap secured at one end to said winding-shaft and detachably connected at its opposite end to the complementary cover.

11. In a ledger, the combination with the complementary covers, of a hollow connecting-post therebetween, a rotary member carried by one of the covers, a flexible binding device extending through the post and connected to the rotary member and complementary cover, and means for rotating the member.

In testimony whereof I affix my signature in presence of two witnesses.

FREDERICK PETERS.
